UNITED STATES PATENT OFFICE

2,404,194

IRONING BOARD

Max Sass, New York, N. Y.

Application November 9, 1944, Serial No. 562,674

1 Claim. (Cl. 38—104)

1

This invention relates to ironing boards, and relates more particularly to an improved ironing table comprising a main board and a novel sleeve-ironing board which normally resides within a suitably formed recess within the main board, and, when in such position, is flush with the upper surface of the board and presents no obstruction during the course of normal ironing operations. When, however, the sleeve-ironing board is to be used, a novel padded cover is slipped from the main body of the board to an advanced position at one end of the board, at which time the sleeve-ironing board may be quickly and easily raised to elevated position where it may be employed for ironing sleeves and other tubular portions of garments.

Ironing boards having sleeve-ironing attachments have been known, but they have been generally unsatisfactory for the reason that when in retracted position relative to the main body of the board, a smooth, unbroken surface for such board was not maintained, and accordingly during the ironing operations ridges were formed in the articles being ironed. In accordance with the present invention, the main board is formed with a longitudinal recess or slot extending inwardly from the larger end of the board substantially half its full length. The sleeve-ironing board is formed with precisely the same contour as that of the recess, except that it has slightly smaller dimensions so that when the pad covering the sleeve-ironing board has been removed, a slight space exists between the outer marginal edges of the sleeve-ironing board and the recess, although when the covering for the latter board is secured in place no recess exists.

Also of importance in the present invention is the fact that the upper surface of the uncovered sleeve-ironing board, when in retracted position, lies slightly below the plane of the upper surface of the main board. The sleeve-ironing board, however, is provided with a padding having an effective thickness equal to the difference between the planes of the two boards when the sleeve-ironing board is in retracted position, and accordingly when this padding is in place, the upper surface of the padded sleeve-ironing board is planar with the uncovered upper surface of the main board. The padding or covering for the supplemental board may be secured along the vertical marginal edges thereof in more or less permanent fashion, and need not be removed, except when so worn or burned as to require re-covering.

The main body of the board is provided with a

2

suitable covering which may be more or less permanently secured to that end of the board opposite the recess, the portion of the covering or padding normally overlying the supplemental board being formed along its marginal edge with a loop which extends over the end wall of the main board adjacent the recess. Also, if desired, an elastic tape may be secured to the edges of the main cover in order to retain the cover in taut position while the main board is being used. When, however, the supplemental board is to be employed, the cover is merely slipped over the end wall of the main board, and the elastic tape draws the covering in the direction of the opposite end of the board, thus exposing the supplemental board, which is then raised to elevated position by a pair of novel links having a parallelogram motion, the links being arranged to have an over-the-center locking action. The main cover is thus completely out of the way, and the sleeve-ironing board may then be used while rigidly supported in this upper position.

Another object of the present invention is to provide an ironing board of the character described which is simple and inexpensive to construct, and which may be used with facility.

In the drawing:

Fig. 1 is a top plan view of one embodiment of the present invention, the view showing, in dotted lines, the position of the supplemental sleeve-ironing board in retracted position, the view further showing the pad structure covering the entire board.

Fig. 2 is a plan view similar to Fig. 1, but showing the free end of the cover or pad in released position, exposing the sleeve-ironing board.

Fig. 3 is an enlarged, vertical section taken on line 3—3 of Fig. 1.

Fig. 4 is a broken side elevation of the board showing the sleeve-ironing board in elevated position.

Fig. 5 is a broken bottom plan view of the board.

The main body of the ironing board is shown at 10, and may be of the usual shape wherein that portion lying at the left-hand end is formed with parallel sides, and that portion at the right-hand end is tapered, as shown at 11. The means for supporting the main board are illustrated generally at 12 and 13, and may comprise the usual folding legs, although the same form no part of the present invention since any leg structure may be employed, or the board may be hinged within a wall recess and be provided at its outer end with only a single leg.

The board is further provided with a recess 14 extending inwardly from the left-hand end thereof, and being of a length equal to substantially half the length of such board. The sleeve board 15 has the identical contour as the opening 14, except that it is of slightly smaller dimensions. It is formed on its upper surface with a padding or covering 16 which extends downwardly, as shown at 17, around the outer marginal edges of such sleeve board, such portion 17 being tacked or otherwise secured to said vertical edges. The sleeve board 15 is so proportioned relative to recess 14 that when the cover 16 and marginal edges 17 thereof are in place, as shown in Fig. 3, there will be no opening between such outer marginal edges of the sleeve board and the edges of recess 14.

It will be noted from an examination of Fig. 3 that the sleeve board 15 is formed from material of slightly lesser thickness than main board 10. The difference between the thicknesses of the several boards is equal to the thickness of the padding 16, and the supporting means herein-after described for the sleeve board are so arranged as to have the upper surface of sleeve board 15 lying below the plane of the main board 10, the padding 16, however, making up for this slight difference, and accordingly when the sleeve board 15 is in retracted position, as shown in Fig. 3, the upper surface of padding 16 is plane with the upper unpadded surface 19 of the main board.

The main board is further provided with a covering 20 which will usually include a padding element, and such covering may be generally of the shape of the main board with excess material around the marginal edges which drape over, and are affixed to the lower edge of the main board. At the right-hand end of the board, these marginal edge portions 21 may be secured to the lower surface of board 10 by means of tacks 22, or other suitable means. To the left of the tacks 22 shown in Fig. 5, the padding 20 is formed with a loop 24 extending around the three sides thereof, and within such loop an elastic element 25 is positioned.

When the sleeve board, as such, is not in use, it will be in lowered position, as shown in Fig. 3, and in such position the padding 20 may be secured around the marginal edges of the main board due to the elastic in the loop, thus giving the main board and the sleeve board an effective all-over covering of padding material. Also, since the upper surface of sleeve board 15 is recessed relative to the upper surface of main board 10, and such recessed area is effectively filled with covering 16 for the sleeve board, the upper surface of the main board, including the sleeve board, will have a perfectly smooth surface which will form no depressions to reduce the quality of the ironing.

The following means are provided for supporting the sleeve board 15, and for raising the same

into elevated position. Substantially "U" shaped elements 26 and 27 are provided at their terminals with studs 28 forming shafts. These shafts are journaled on the lower surface of the main board by means of bearing members 30. The central portions 31 and 32 of elements 26 and 27 are also journaled to the sleeve board 15 by means of bearing elements 34. Studs 28 have stop portions 37 which are so disposed relative to the main body of elements 26 and 27 as to engage the lower surface of board 10 when the board has been raised to elevated position through an arc of more than 90°, as shown in Fig. 4. One stop member in U shaped element 27 is replaced by a crank portion 40 having a handle 41 at its outer terminal. A plate 46 secured on the lower surface of the main board overlies a portion of opening 14, and thus limits downward movement of the supplemental sleeve board.

It will be seen from the foregoing, that when the sleeve board is in its lowermost position, its upper padded surface is plane with the upper unpadded surface of main board 10, and when the padding 20 occupies the position shown in Fig. 1, the ironing surface will have an all-over smoothness. The pad covering 20 may be instantly released, and the elastic element 25 therein draws it to the position shown in Fig. 2, which then permits the supplemental board to be raised upwardly to the position shown in Fig. 4, in which position it is perfectly rigid since the weight of the iron and of the material being ironed effectively locks the supplemental sleeve board in this position.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein, but that extensive deviations from the illustrated form or embodiment of the invention may be made without departing from the principles thereof.

What I claim is:

In an ironing board assembly, the combination of a main ironing board having an elongated opening therein, a supplemental sleeve-ironing board of substantially the same size as the opening and normally positioned therein, a resilient pad covering the upper surface of the sleeve board, the upper surface of the pad normally being planar with the upper surface of the main board, a pad normally covering the main board and the sleeve board and being removable therefrom, and means for raising the sleeve board to an elevated position substantially parallel with the main board when the removable pad has been removed.

MAX SASS.
